UNITED STATES PATENT OFFICE.

EDWARD J. H. ELLINGEN, OF MINERAL POINT, WISCONSIN.

STOVE-LIFTER.

1,122,374.

Specification of Letters Patent. Patented Dec. 29, 1914.

Application filed November 6, 1913. Serial No. 799,567.

To all whom it may concern:

Be it known that I, EDWARD J. H. ELLINGEN, a citizen of the United States, residing at Mineral Point, in the county of Iowa and State of Wisconsin, have invented certain new and useful Improvements in Stove-Lifters, of which the following is a specification.

My invention relates to stove lifters and the primary object of my invention is to provide a novel means for connection with a lifter for firmly gripping the lid of a stove and allowing the lid to be carried from place to place without any danger from falling upon the floor or elsewhere when held in different positions.

Another object of my invention is to provide an improved adjusting means which allows the foot of the lifter to be accommodated to the openings in different sized lids.

A further object of my invention is to provide an improved means for holding the gripping plate in normal position upon the shank of the lifter.

A still further object of my invention is to provide a device that is simple in construction, efficient in operation, and one that can be manufactured and put upon the market at a minimum cost.

Other objects as well as the nature, characteristic features and scope of my invention will be clear from the following description taken in connection with the accompanying drawings.

In the drawings, Figure 1, represents a side elevational view of my improved lifter applied to the opening in a lid. Fig. 2, represents a top plan view of my invention. Fig. 3, represents a longitudinal sectional view of the gripping plate. Fig. 4, represents a side elevational view of the lower end of the lifter with the gripping plate removed.

Referring more particularly to the drawings in which similar reference numerals designate like or corresponding parts, the numeral 1, represents a lid of a stove which has formed therein an ordinary depressed portion 2, which depressed portion has extending from its lower end a recess 3, the upper face of which is beveled as shown at 4, to form a guide or the like for my improved lifter 5, when the same is being inserted into the recess. It may be understood that I do not limit myself to this particular form of depressed portion and recess,

but the same is generally the form employed, and I have described the same for the purpose of clearly illustrating my invention.

The lifter 5, comprises a shank 6, which has formed at its lower end a foot 7, that has substantially the same contour as the depressed portion 2, and which foot has extending from its forward end a substantially flat toe 8, adapted for insertion in the recess 3. The upper end of the shank 6, is reduced as at 9, and has secured thereto by means of rivets or the like 10, the reduced end portion 11, of a handle 12, which handle has its upper end curved slightly to accommodate a suitable engaging surface for the hand of the operator, (not shown).

For the purpose of holding the foot 7, securely within the depressed portion 2, to prevent the lid from falling upon the floor, I have provided a substantially oval-shaped gripping plate 13, which has provided therein, intermediate its ends, a longitudinal slot 14, through which is arranged the raised portion 15, formed integral with the upper part of the foot 7. In order to hold the gripping plate in normal position, I have pivotally and removably mounted the same in adjusting openings 16, by means of a bolt 17, which also passes through the ears 18, formed upon the sides intermediate the ends of the longitudinal slot 14. A nut 19, is threaded upon the free end of the bolt 17, so that in case the depressed portion 2, is of a greater depth than the ordinary form, the bolt may be removed from the lower of the adjusting openings 10, and passed through the adjacent opening. For the purpose of more securely holding the gripping plate 13, in normal position upon the shank 6, I have provided the rear edge thereof with teeth 20, adapted to be engaged by the rear end of the longitudinal slot 14, when the foot 7, is in position in the depressed portion 2.

It will be noted that when the toe 8, and the foot 7, are in the recess 3, and depressed portion 2, the plate 13, being of a longitudinal oval shape, surrounding the body of the plate, will rest on the lid 1, and the action of lifting the lid off the stove causes the rear end of the foot 7, to be jammed and forced against the rear end of the depressed portion 2, in which it is engaged, thereby forcing the plate 13, to engage the portion of the lid surrounding the depressed portion 2.

Although I have shown and described the preferred embodiment of my invention, I desire to be understood that I am not to be limited to the exact details shown, however, great stress is laid upon the arrangement and coöperation of the gripping plate with the teeth on the rear edge of the shank. By this arrangement, the gripping tendency of the plate is greatly increased without interfering with or weakening the pivotal securing means of the plate and further reducing strain on the pivot point to a minimum, thus increasing the durability of the device. Again it is essential that the gripping plate be flat and engaged upon the surface of the stove lid about the opening therein.

From the above description taken in connection with the accompanying drawings, it can easily be seen that I have provided a device that is simple in construction, containing but a few simple parts that can be cheaply manufactured and assembled and when assembled can be placed upon the market and sold at a minimum cost.

It will be understood that the above description and accompanying drawings comprehend only the general and preferred embodiment of my invention and that various minor changes in detail of construction, proportion and arrangement of the parts may be made within the scope of the appended claims and without sacrificing any of the advantages of my invention.

Having thus fully described my invention what I claim as new and desire to secure by Letters Patent is:

1. In combination with a lifter having a plurality of serrations on the rear edge adjacent the outer end thereof, of a plate pivotally secured to the shank of said lifter and adapted for engagement with the serrations when the lifter is in position for facilitating the gripping of a stove lid.
2. The combination with a lifter having a plurality of serrations on the rear edge ad-

jacent the outer end thereof, of a substantially oval-shaped plate, said plate being slotted longitudinally and pivotally mounted about the shank of said lifter, and the rear end of the slot being engageable with the serrations for facilitating the gripping and holding of a stove lid.

3. A stove lid lifter including a shank, a foot formed upon said shank, a toe integral with the forward end of the foot, said foot and toe adapted for insertion in a stove lid, a plate pivotally secured upon the opposite side of said shank and extending beyond the edges of the opening, means for adjusting said gripping plate, and means on the shank coöperating with the plate for facilitating the gripping and holding of a stove lid.

4. A stove lid lifter including a shank, a foot formed upon said shank, a substantially flat toe formed upon the forward end of said foot, said foot and said toe adapted for insertion in an opening of a stove lid, a plurality of teeth provided on the rear edge of the shank adjacent the lower end thereof, a substantially oval-shaped plate having a longitudinal slot therein, ears formed upon the sides of said slots intermediate the ends thereof, said plate arranged upon the opposite sides of said shank and pivotally mounted through said ears to said shank, said plate being flat and arranged in engagement with the upper surface of a lid about an opening therein when the shank is in position, and the rear end of the slot being engageable with said teeth for facilitating the gripping and holding of a stove lid and for increasing the efficiency thereof without weakening the securing means of the plate.

In testimony whereof I affix my signature in presence of two witnesses.

EDWARD J. H. ELLINGEN.
